Primary Examiner—Ian Simmons*Assistant Examiner*—R. Johnson(74) Attorney, Agent, or Firm—Eric Karich(57) CLAIM

The ornamental design for a “detachable pocket for pants,” as shown and described.

DESCRIPTION

FIG. 1 is a perspective view of a detachable pocket for pants, showing my new design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.

The broken line showing of a pair of pants is for illustrative purposes only and forms no part of the claimed design.

The broken lines shown on the surface of the pocket in FIGS. 1 and 2 represent stitching.
